UNITED STATES PATENT OFFICE.

ISAAC H. SHAMBAUGH, OF AVILLA, INDIANA.

CLOTHES RACK.

Application filed January 11, 1927. Serial No. 160,459.

This invention relates to furniture and more particularly to a clothes rack of the cabinet type. One object of the invention is to provide a clothes rack which will be attractive in appearance and so constructed that it may carry hats, coats and other garments and also provide a support for a suitcase.

Another object of the invention is to provide a garment hanger especially designed for use in hotels and rooming houses catering to transient guests who do not always desire to completely unpack their suitcases and other baggage during the time they occupy a room.

Another object of the invention is to provide a piece of furniture of the character set forth which may be used as a dresser, as well as a garment container and support for a suitcase.

The invention is illustrated in the accompanying drawings wherein,

Figure 1 is a view showing the improved garment hanger in front elevation.

Figure 2 is a vertical sectional view through the garment hanger.

Figure 3 is a rear elevation thereof.

Figure 4 is a transverse sectional view taken on the line 4-4 of Figure 3.

The garment hanger constituting the subject matter of this invention is formed with a body portion or cabinet 1 having a rear wall 2, a top 3, a bottom 4, and side or end walls 5. The side walls 5 are preferably of an open construction and each consists of upper and lower head bars 6 and 7 carrying vertically disposed rungs 8 and at their ends secured to the front and rear bars 9 and 10. Baffle strips 11 extend across the lower portions of the rungs 8 so that small articles placed upon the bottom 4 of the cabinet will not be liable to slip through the spaces between the rungs and drop upon the floor where they are liable to be broken or become lost.

The rear wall is secured against the rear bars 10 and the bottom 4 may have its ends resting upon the lower cross bars 7 and recessed at the corners to receive portions of the front and rear bars 9 and 10.

By referring to Figures 1 and 2 it will be seen that the front bars 9 of the cabinet constitute the upper end portions of standards 12, the lower ends of which rest upon the floor. Rear standards 13 are also provided to assist in supporting the cabinet

and preferably consist of front and rear sections 14 and 15 spaced from each other a sufficient distance to receive the end portions of the cross strips 16, 17 and 18 which extend between the two rear standards. 60

Nails or other suitable fasteners may be employed to secure the ends of the cross strips between the front and rear sections of the standards 13. It will also be noted that there has been provided braces 19 which extend between the cross strips 17 and 18 and serve to prevent them from moving out of proper spaced relation to each other. Yokes or bolsters 20 extend transversely across the upper strip 16 and are secured to

the under face of the bottom or lower wall of the cabinet in order to strengthen the cabinet and prevent danger of the bottom thereof splitting. Adjacent their lower ends the front and rear standards 12 and 13 70

are connected by upper and lower cross bars 21 and 22, the rear ends of which are secured to short legs 23. It should be noted that the base of the stand of which the bars 21 and 22 form a part, projects rearwardly 80 from the rear standards 13 and that the projected end portions of the upper cross bars 21 carry a board 24 upon which a suitcase or the like may be placed. The rear legs 23 and lower end portions of the sections 14 of the standards 13 are braced by rungs 25 and 26 which serve to prevent them from moving out of proper spaced relation to each other. It will thus be seen that the clothes hanger is formed with a frame work 85 having a very strong construction and will not be liable to become rickety.

In order to suspend coats and other garments there have been provided supporting hooks 27 and 28. The hooks 27 are of a conventional construction and provided with the usual threaded stem so that they may be screwed into opposite faces of the cross strip 16. The hooks 28 are somewhat similar to the hooks 27, but provided with upper and lower eyes 29 through which rods 30 pass, the ends of which are anchored in the strips 16 and 17. It will thus be seen that the hooks 28 are rotatably mounted upon the rods 30 and may be turned, as indicated by dotted lines in Figure 4, and selectively caused to project either forwardly, or rearwardly, according to the wishes of the person using the hanger. It will thus be seen that coats and other garments may be sus- 110

pended either in front of or to the rear of the cross strips and in either case will be disposed beneath the bottom of the cabinet where they will be shielded from dust.

5 The top or super structure 31 of the hanger is formed with a back-board, or rear wall 32 from which a top 33 and shelves 34 and 35 project. The forward portions of the top and shelves are supported by 10 short standards 36. If desired, the top 33 may be provided with an ornamental cross strip 37, at its front, and the standard 36 may be ornamented, as shown at 38. The top or super structure is securely but releasably held in place upon the top of the cabinet by supports 39 which preferably consist of wooden strips releasably secured to the back board 32 and rear wall 2 by screws or other removable fasteners. A mirror 40 is 20 secured against the forward face of the back-board between the shelves 35 in any desired manner for use by a person in a room in which the clothes hanger is placed.

25 When the clothes hanger is in use a suitable case may be placed upon the seat or shelf 24 and coats and other garments hung upon the hooks 27 and 28. Shirts and the like may be placed in the cabinet upon the bottom 4 thereof and brushes or other articles placed 30 upon the top 3 or shelves 34 and 35. It will thus be seen that the garment hanger will be found very convenient for transient guests of a hotel or rooming house.

Having thus described the invention, I 35 claim:

1. A clothes rack comprising a frame including a body, standards depending from opposite sides of said body, certain of the standards being disposed at the front of the 40 body and others intermediate the depth thereof, a base connecting said standards and having a portion projecting beneath the rear portion of said body to form a shelf, cross strips extending between the rear standards, 45 pivot rods carried by said strips, and garment

hooks loose upon said rods and adapted to be turned to project from selected sides of the strips.

2. A clothes rack comprising a frame including a body, standards depending from opposite sides of said body, certain of the standards being disposed at the front of the body and others intermediate the depth thereof, a base connecting said standards and having a portion projecting beneath the rear portion of said body, said base consisting of side bars connecting the lower end portions of said standards and projecting rearwardly therefrom, supporting legs for the rear ends of said side bars, and a top board resting upon and secured to said legs and the rearwardly projected portions of said side bars and constituting a seat, cross strips connecting the upper portions of the rear standards, and garment suspending elements carried by said cross strips.

3. A clothes rack comprising a body open at its front and having a top, a bottom and side and rear walls, front standards depending from said side walls, rear standards depending from the body intermediate its depth and having their upper ends secured to the side walls, vertically spaced cross strips extending between and secured to the rear standards, reinforcing yokes for the bottom secured against the under face thereof and extending transversely across and resting upon the upper edge of the upper one of said cross strips, garment suspending elements carried by certain of said cross strips, side bars connecting the lower end portions of said standards and projecting rearwardly from the rear standards, supporting legs for the rear ends of said side bars, and a seat board secured upon the upper ends of said legs and projected rear end portions of said side bars.

In testimony whereof I affix my signature.

ISAAC H. SHAMBAUGH. [L.S.]
